Nicholas Muller's Design for a CLOCK FRONT

4450

PATENTED NOV 1 1870

August Wiedenhein
Charles Kibbey

Nicholas Muller

United States Patent Office.

NICHOLAS MÜLLER, OF NEW YORK, N. Y.

Design No. 4,450, dated November 1, 1870.

DESIGN FOR A CLOCK-FRONT.

The Schedule referred to in these Letters Patent and making part of the same.

To all whom it may concern:

Be it known that I, NICHOLAS MÜLLER, of the city, county, and State of New York, have invented a new and ornamental Design for a Clock-Front; and I do hereby declare that the following is a full, clear, and exact description thereof, which will enable those skilled in the art to make and use the same, reference being had to the accompanying photograph forming part of this specification, in which the design is represented by a front view.

This invention relates to a design for a useful and ornamental clock-front.

The dial *d* is situated in the upper portion of the design.

The portion immediately over the dial *d* is formed by a series of ornaments, on each side of which is a button, from which emanate ornamental curves, forming part of the top edge.

This series of ornaments is surmounted by a pedestal, supporting a fancy urn containing flowers and leaves.

Encircling the dial *d* is a chain of ornaments.

The upper part of each side edge is formed by

Egyptian arabesques *a*, from each of which hangs a branch of laurel leaves and fruit.

The space between the dial and base or lower part of the design, (separated from the upper portion by the line of division *l*), in the center, is occupied alternately by plane surfaces and grooves, and the side is embellished by arabesques.

The main feature of the lower portion of the design consists in a large ornamental leaf, *m*, from which originate smaller leaves and a twig of buds and flowers diverging to the sides, being the same on both sides of the leaf *m*.

On each of the corners is a large scroll-like ornament, giving the whole an elegant and finished appearance.

What I claim as my invention, and desire to secure by Letters Patent, is—

The design for a clock-front, as herein shown and described.

Signed by me this 14th day of October, 1870.

Witnesses: NICHOLAS MÜLLER.
AUGUST WIEDERKEHR,
CHARLES KITSCHELT.
